UNITED STATES PATENT OFFICE.

WILLIAM R. COCHRAN, JR., OF TOLEDO, OHIO.

OIL-BURNER.

1.057.937.

Specification of Letters Patent.

Patented Apr. 1, 1913.

Application filed March 13, 1912. Serial No. 683,525.

To all whom it may concern:

Be it known that I, WILLIAM R. COCHRAN, Jr., a citizen of the United States, residing at Toledo, in the county of Lucas and State 5 of Ohio, have invented certain new and useful Improvements in Oil-Burners; and I do hereby declare the following to be a full, clear, and exact description of the invention, such as will enable others skilled in 10 the art to which it appertains to make and use the same.

My invention relates to an improvement in oil burners, the object being to provide an oil burner for stoves or other heating apparatus which will be simple, economical and durable in its construction and of high efficiency in its operation.

With these objects in view my invention consists in certain features of construction 20 and combinations of parts as will be hereinafter described and pointed out in the claims.

In the accompanying drawings, Figure 1 is a view partly in transverse section and 25 partly in end elevation of one embodiment of my improvement; Fig. 2 is a view in side elevation of my improved burner detached from the stove; Fig. 3 is a view in end elevation of the burner; Fig. 4 is a view partly 30 in side elevation and partly in longitudinal section of the burner and its supporting frame; Fig. 5 is a transverse section of the burner and Fig. 6 is a plan view of the same.

1 represents a supporting frame consisting of the side plates 3, top plates 2 and end plates 4. The top plate is provided with ribs 2^a so as to form a tray 2^b to receive dripping, etc. The burner comprises two parallel pipes 5 and 6. The lower pipe 5 is 35 preferably of smaller diameter than the upper pipe, and is supported in vertical grooves 7 formed in the transverse deflector plates 8 by which they are retained against accidental displacement. Pipes 5 and 6 are 40 connected at one end by means of the elbow pipe couplings 9, which fit between the inwardly projecting flanges 10 integral with one end plate 4 of the supporting frame which are separated at their upper ends to 45 permit the closed ends of the pipes to be inserted vertically between the flanges which support the closed end of the pipes against displacement, the end plate 4 at the opposite end of the supporting frame being 50 provided with a slot, open at its upper end so as to permit the burner to be readily as- sembled in and removed from its supporting frame. The opposite end of the lower pipe is closed by a cap or plug 11, while the upper pipe is provided with curved 55 couplings to which the oil supply pipe 12 is secured. Oil is supplied to the upper pipe or tube from a tank 13 located sufficiently above the burner to insure any desired heat or pressure of oil thereto, and the 60 supply is regulated by means of a needle valve 14.

In the particular embodiment illustrated in the drawings, the lower pipe 5 is provided with two burners 16, each of which is formed by a pin hole 17, in the upper wall of the pipe near its end, and oppositely inclined longitudinal grooves 18 are formed in the upper wall of the pipe and communicating with the pin hole, thereby permitting any unvaporized oil that may escape through the exit to collect in the groove and be consumed by the burner flame.

The upper pipe 6 is provided with spreaders 19, each of which is located immediately 65 over one of the burners on the lower pipe and in such proximity thereto that the burner flame will impinge against the lower and upwardly inclined walls 20 of the spreader and be thereby transformed into 70 an annular flame which may be used for cooking or other purposes. An exceedingly hot flame and substantially perfect combustion of the oil is secured by the intimate admission of air to the jet of escaping oil 75 through the circular openings 21 in the transverse deflecting plates 8, which insures a free inlet of air all around and in intimate contact with the escaping jet of oil and gas. Spreaders 19 may be made of any de- 80 sired metal and secured to pipe 6, or they may be cast integral therewith. They are of sufficient size, weight and shape to not only form an annular flame, but serve to absorb heat and assist in vaporizing oil 85 flowing through the pipe and convert it into gas and highly heated vapor.

The supply of oil to the burner is regulated by the valve 14 and passes into the upper pipe which is highly heated by the 90 flames issuing from the burners on the lower pipes and also by the heat conducted thereto by the spreaders, and the highly heated gas and vaporized oil is conducted to the lower pipe and escapes through the small 95 exit holes formed therein as has already 100 been explained.

From the foregoing it will be noted that the oil burner is exceedingly simple in its construction and may be manufactured at small initial cost, as it is mainly composed 5 of stock pipes or tubing and elbow joints which may be readily cut into any desired lengths and assembled for use.

The frame in which the burner is supported is provided with closed side and end 10 plates and with a top plate which is closed at all points excepting at the circular openings 21 and hence air which enters through the grate in which the burner is supported flows upwardly into the space in the under- 15 side of the supporting frame and escapes therefrom through the openings 21 where it commingles with the oil and gases issuing through the burners and insures a perfect combustion and an exceedingly hot flame.

20 While I have illustrated one embodiment of my invention it is evident that it may be applied in various ways to ranges and stoves and hence I would have it understood that I do not restrict myself to the 25 particular construction shown and described.

Having fully described my invention what I claim as new and desire to secure by Letters-Patent, is:—

30 1. The combination of an oil supply pipe thickened and enlarged at points to form flame spreaders, a burner pipe connected with the oil supply pipe and provided with a burner for each flame spreader, each 35 burner being located under its spreader, and a supporting frame comprising a top plate and two end members projecting above the top plate, one end member being slotted 40 for the insertion of the oil supply pipe, and the other provided on its inner face with

flanges adapted to receive between them the coupling connecting the oil supply and burner pipes whereby the oil supply pipe is maintained in position above the burner pipe.

2. An oil burner comprising an oil supply pipe and a burner pipe, the oil supply pipe being located vertically above the burner pipe and having a plurality of separated solid bodies of metal integral therewith and projecting at the sides to form spreaders for the flame, and the burner pipe having exits for oil and gas, the said exits being located under the flame spreaders on the oil pipe, and also having longitudinal grooves 55 projecting in both directions from said exits.

3. The combination of an oil supply pipe, a burner pipe, the latter being in the plane of and below the oil supply pipe, and provided with a burner, an elbow connecting the two pipes and a burner supporting frame comprising a top plate and side and end plates, the end plates projecting above the top plate and one slotted to receive the 60 oil pipe and the other provided on its inner face with parallel flanges to support the elbow connecting the two pipes, and the top plate provided with an air opening located immediately under the burner on the burner 65 pipe, and with deflecting surfaces at the sides of the air opening for deflecting the air upwardly to the burner.

In testimony whereof, I have signed this specification in the presence of two sub- 70 75 scribing witnesses.

WILLIAM R. COCHRAN, JR.
